UNITED STATES PATENT OFFICE.

CHARLES CHESWRIGHT, OF LONDON, ENGLAND.

MACHINE FOR CAPSULING BOTTLES.

SPECIFICATION forming part of Letters Patent No. 258,890, dated June 6, 1882.

Application filed February 15, 1882. (No model.) Patented in France November 10, 1881, No. 145,750.

To all whom it may concern:

Be it known that I, CHARLES CHESWRIGHT, a subject of the Queen of Great Britain, and residing in London, England, have invented 5 certain Improvements in Machines for Capsuling Bottles, of which the following is a specification.

The object of my invention is to provide a simple machine which shall be capable of employment in capsuling bottles of different sizes, and which shall afford ample facility for watching the operations.

In the drawings which serve to illustrate my invention, Figure 1 is a front elevation of my 15 improved machine, and Fig. 2 is a vertical mid-section of the same, taken at right angles to Fig. 1.

A is a press-frame, and B is a screw-plunger, mounted therein and operated by a lever or 20 hand-wheel, L.

C is a metallic boxing, arranged to slide in the frame A, and coupled to the screw B in a well-known way.

C' is also a metallic boxing, constructed like 25 C, mounted to slide in the frame A and upheld by a strong spring, E.

In the boxes C C' are fixed by dovetails two semicircular segments, D D', of vulcanized rubber, which, when brought together, as in Fig. 30 1, form a circular opening. The points a a, where these rubber segments contact, are cut on a bevel or angle of about forty-five degrees, as shown, and these serve to plait or fold the surplus metal of the capsule, as indicated at b 35 in Fig. 2.

When it is necessary to make more than two plaits, as in the case of large capsules, recesses or grooves may be cut or formed in the inner faces of the segments D D' at their centers.

40 To permit the operator to adjust the bottle bearing the capsule readily in the press, so as to bring the shoulder on the bottle-neck at the

proper point relatively to the clamping-segments, I mount a fixed nut, I, on the lower boxing, C', and mount in this nut a screw, G, 45 provided with a disk, F, on its end, and an operating wheel or crank, H. It is only necessary to set the disk F properly, and the operator may then enter the bottle-neck until the head of the capsule touches the said disk. 50 This device forms a simple and readily-adjustable gage.

The rubber segments being of a yielding material, their use enables my machine to be employed without changing the segments for a 55 wide range of bottles having necks of different sizes and shapes.

Having thus described my invention, I claim—

1. A machine for capsuling bottles, having 60 semicircular clamping and plaiting segments made from an elastic and yielding material, whereby said segments are enabled to adapt themselves to bottle-necks of various shapes and sizes, as set forth. 65

2. The combination, to form a capsuling-machine, of a press-frame and screw and upper sliding boxing coupled to the screw, a lower sliding boxing elastically mounted, and the rubber segments D D', all constructed and arranged substantially as set forth. 70

3. The combination of the frame A, screw B, boxings C C', rubber segments D D', springs E, nut I, screw G, and disk F, all constructed and arranged to operate substantially as set 75 forth.

In witness whereof I have hereunto signed my name in the presence of two subscribing witnesses.

CHARLES CHESWRIGHT.
